UNITED STATES PATENT OFFICE.

CHARLES H. BOWMAN, OF WASHINGTON, DISTRICT OF COLUMBIA.

DESIGN FOR A VEHICLE-BODY.

58,542.

Specification for Design.

Patented Aug. 2, 1921.

Application filed February 19, 1920. Serial No. 359,939. Term of patent 14 years.

To all whom it may concern:

Be it known that I, CHARLES H. BOWMAN, a citizen of the United States, residing at Washington, in the District of Columbia, have invented a new, original, and ornamental Design for Vehicle-Bodies, of which the following is a specification, reference being had to the accompanying drawing, forming part thereof.

The figure is a perspective view of a vehicle body, showing my new design.

I claim:

The ornamental design for a vehicle body, substantially as shown.

In testimony whereof I affix my signature.

CHARLES H. BOWMAN.
